WALTER M. CROSS, OF KANSAS CITY, MISSOURI.

STEAM-GENERATING SYSTEM.

1,059,980.

Specification of Letters Patent. Patented Apr. 29, 1913.

Application filed September 15, 1911. Serial No. 649,480.

To all whom it may concern:

Be it known that I, WALTER M. CROSS, a citizen of the United States, residing in the city of Kansas City, county of Jackson, and 5 State of Missouri, have invented certain new and useful Improvements in Steam-Generating Systems, of which the following is a specification.

This invention relates to improvements in 10 steam generating systems, and in the present instance is shown as used in connection with a liquid hydrocarbon burner, although in its broader aspects the invention is not necessarily confined to such use.

15 Among the salient objects of the invention are to provide a construction in which a substantial equilibrium is normally maintained between the pressure of the water supply and the steam pressure in the generator and 20 in such a way as to prevent the generator pressure from substantially exceeding the pressure of the water supply independently of the temperature of the generator; to provide a construction of the above character

25 which dispenses with the necessity of the usual spring or other safety valves for the generators, and in which the heat units which are ordinarily lost in the popping off of a steam safety valve are retained, and 30 utilized in the generator pressure; to provide a construction in which the water supply is normally fed to the generator through a restricted feed orifice of predetermined capacity but in which the water or steam in 35 the generator may nevertheless back freely and at once into the water supply when the pressure in the generator exceeds the pressure of the water supply; to provide a construction in which the pressure of the water

40 supply and generator are maintained at all times at substantial constant equilibrium under normal loads, or in other words a construction in which under normal loads the steam pressure on the generator will

45 neither exceed nor fall below the water pressure; to provide a construction in which the steam generator automatically maintains its pressure at substantially the same pressure as the water supply although the latter may 50 vary; to provide a construction which is

particularly adapted for use where safety and simplicity of operation and avoidance of escaping steam or hot water, are necessary, as in a dwelling; to provide a construction which is particularly applicable for 55 use with hydrocarbon oil burners and which automatically regulates itself and can be effectively and safely run by any unskilled operator; to provide a construction which in its application to hydrocarbon oil burners 60 both automatically feeds oil and regulates the atomizing steam jet, and at the same time avoids any danger of fire or explosion by the over-flow of oil or excess of steam pressure; to provide a construction 65 which in its broader aspects, is as stated, adapted to a wide range of uses, and which is nevertheless economical both in construction and operation and in general to provide an improved construction of the character referred to. 70

The invention consists in the matters hereinafter described and more particularly pointed out in the appended claims.

In the drawings—Figure 1, is an elevation 75 of a hydrocarbon burner system equipped with my invention; Fig. 2 is an enlarged detail view of the nebulizer; Fig. 3 is a sectional view of a modified form of the valve construction used in the invention. 80

Referring to the drawings—1 designates a furnace wall of any suitable construction having a fuel opening 2. Within the furnace is a nebulizer 3, the cylinder 4 of which has a nozzle 5 at its inner end through which 85 vapor may be discharged into the furnace chamber. This nozzle preferably has a contracted port 6, having flaring sides 7 as shown in Fig. 2. A fuel supply pipe 8 communicates with the lower side of the nebulizer and at its other end leads to a supply tank 9. The pipe 8 is provided with a controlling valve 10. Extending through the cylinder of the nebulizer is a steam pipe 11 having a tip 11' which projects into the nozzle as shown. The outlet of the pipe 11 is controlled by a valve member 12 and at its inlet end communicates with a conduit 11^a leading to an air pump 14. The upper end 95 of the pipe 11^a connects to one end of a 100

closed steam coil 15 placed in the furnace chamber. A steam gage 13 is also provided as shown.

The steam coil or generator 15 is connected at its other end with a supply or service pipe 16 which may lead from any suitable source of water supply under pressure such as a city main or tank (not shown). The pipe 16 is provided with a 10 needle valve 18 to control the supply of water from the service pipe to the coil. To the pipe 16 is connected a branch conduit 19, the ends of which are connected to the supply pipe at opposite sides of the controlling valve 18 as shown. The pipe 19 is provided with a freely moving check valve or flap valve 20, which is so arranged as to open against pressure from the right hand side of the pipe or the side leading to the 20 coil 15, but closing against pressure from the left hand side of the pipe 19 or from the pressure side of the water supply.

The operation of the invention may be briefly described as follows: The oil controlled valve 10 is opened and the air is 25 compressed through the pump 14 through the nozzle 6 of the nebulizer whereby the oil is drawn from the tank 9 by suction and forced out of the nozzle in the form of a 30 spray where it is ignited for the purpose of heating the coil 15. As soon as the coil becomes sufficiently heated the valve 18 is open allowing the water to enter the hot coil 15. The pump 14 may then be shut off as the 35 generated steam will pass through the pipe 11^a into the nebulizer and take the place of the air. In other words, as the steam is formed in the coil it passes into the nozzle to draw oil from the supply tank and spray 40 the same in the burner. By regulating the valve 12 the proper quantity of steam will always enter the nozzle. At the same time the parts are so arranged that the steam pressure will never be raised above a 45 predetermined or given pressure.

The foregoing is accomplished in the construction shown in Fig. 1 by means of the by-pass or pipe 19 and check valve 20. If the pressure in the generator be suddenly 50 raised as is frequent in constructions of this type, above the water pressure, the hot water and more or less steam, will be forced through the pipe 19 into the supply pipe 16. This results from the fact that the pressure 55 from the generator being greater than the water pressure will open the check valve 20 and in effect push back or stop the flow of water through the restricted opening controlled by the valve 18. If the pressure in 60 the steam generator should be above normal a considerable amount of steam might be forced out of the generator back into the water supply. In practice, however, the steam gage 13 will show but slight varia-

tions in pressure. This results from the fact 65 that as soon as the generator pressure begins to slightly exceed the water pressure it will stop the inflow of the latter and back out through the by-pass 19. This will at once lower the steam pressure to normal where- 70 upon the supply can again feed through the restricted opening controlled by the valve. Of course if the supply of steam in the generator were drawn off freely through the pipe 16, as for example, if the steam were 75 used for some other purpose, the pressure would fall considerably below the water pressure. In commercial practice however, this is not contemplated as the steam is so generated as to take care of normal loads. 80 In constructions of this character it is advisable or necessary that the water supply be fed through a restricted feed opening and it may be also advisable or necessary to draw the steam off through a similar restricted 85 outlet as for example, the passage controlled by the valves 12. At the same time the pressure in the generator may suddenly rise above that which can be taken care of by the restricted inlet and outlet passages referred 90 to. If no safety valves or other means for free escape of steam were provided an explosion would obviously result.

By means of the construction shown in the drawings a free passage for the escape 95 of steam is not only provided *i. e.*, the by-pass 19 and the freely open check valve 20, but the arrangement will prevent any excessive steam pressure. It is to be particularly noted that the arrangement is such 100 that the generator pressure can never more than slightly exceed the water pressure for the reason that the moment the hot water or steam in the generator backs into the water supply the steam pressure is lowered. 105 The present construction does away with any spring controlled check valve, the disadvantages of which are too well known to need elucidation. Further, a minimum loss of heat is obtained for the reason that the 110 hot water or steam that backs into the water supply will be first to reenter the generator and in addition no steam escapes as in ordinary boiler constructions. As is well known in boiler constructions, when the safety 115 valve "blows off" or "pops off," the pressure will be lowered below the blow off pressure of the valve. This results in a further loss in heat. Where a hydrocarbon boiler is used as in a dwelling, the escape of 120 steam into a room is of course very undesirable. The present invention also obviates any danger from sudden lowering of pressure in the water supply or loss of water. This results from the fact that in the present 125 invention the steam pressure will never exceed the pressure in the water supply and does not depend upon a predetermined pres-

sure of a spring valve. If for example, the pressure of the water supply is normally thirty pounds, then thirty pounds of steam may be safely generated. If however the 5 pressure drops to fifteen pounds the steam pressure will also automatically drop to fifteen pounds. This is an important feature of the present invention. Finally, one of the advantages of the present invention is 10 its extreme simplicity and its ability to automatically regulate itself.

Hydrocarbon oil burners for use in a dwelling must frequently be regulated by unskilled operators and are subjected to the 15 danger of the restricted feed or inlet passages, if stopped or clogged and the water pressure being suddenly lowered below normal or entirely cut off. Under the present invention such conditions will not only result in no danger from explosions but none 20 of the steam will escape into the air causing annoyance and be lost.

In Fig. 3 I have shown a modified form 25 of construction in which the valve comprises a diaphragm 21 in a casing 22 inserted in the pipe 16. The diaphragm has an aperture 23 provided with a seat for the ball 24. The sides of the aperture are grooved to allow a small amount of water to pass around 30 the ball when in normal position. When this modified form of construction is used the water from the service pipe or supply pipe will pass through the apertured groove in sufficient quantities to feed the coil. If 35 however the pressure in the generator exceeds the water pressure the hot water and steam in the generator may kick back the ball valve and freely escape into the water supply.

40 The invention is not limited to the details of construction shown except as set forth in the appended claims.

I claim as my invention:

1. The combination with a source of water 45 supply under pressure, of a steam generator, means for heating said generator, connections between said water supply and said generator, said connections having a restricted feed orifice, means automatically permitting a free unrestricted flow of water or 50 steam from said generator back into the discharge end of said water connections when the steam pressure in said generator exceeds the water pressure from said source of supply, thereby maintaining a substantial equilibrium between said pressures under 55 normal load and preventing said steam pressure from substantially exceeding said water pressure without substantial loss of any heat.

60 2. The combination with a source of water supply under pressure, of a steam generator, means for heating said generator, connections between said water supply and said generator, said connections having a re-

stricted feed orifice, means automatically 65 permitting a free unrestricted flow of water or steam from said generator back into the discharge end of said water connections when the steam pressure in said generator exceeds the water pressure from said source 70 of supply, thereby maintaining a substantial equilibrium between said pressures under normal load and preventing said steam pressure from substantially exceeding said water pressure without any substantial 75 loss of any heat units, said equilibrium operating independently of variations in said water pressure.

3. The combination with a source of water supply under pressure, of a steam generator, 80 means for heating said generator, connections between said water supply and said generator, said connections including a constantly open restricted feed orifice, a steam utilizing member, means for a constant restricted flow of steam from the generator to 85 said steam utilizing member, means automatically permitting a free unrestricted flow of water or steam from said generator back into the discharge end of said water connections when the steam pressure in said generator exceeds the water pressure from said source of supply thereby maintaining a substantial equilibrium between said pressure under 90 normal load and effectively preventing 95 said steam pressure from substantially exceeding said water pressure.

4. The combination with a source of water supply under pressure, of a steam generator, means for heating said generator, connections between said generator and water supply, said connections having a restricted feed orifice, and a safety valve for said generator, said valve mechanism being normally closed by water pressure. 105

5. The combination with a source of water supply under pressure, of a steam generator, means for heating said generator, connections between said generator and water supply, said connections having a restricted feed orifice and a safety valve for said generator, said valve mechanism being normally closed under fluid pressure. 110

6. The combination with a nebulizer, of a steam generator, a water service pipe, connections between the service pipe and the generator, said connections including a restricted feed orifice, valve mechanism for the generator, said valve mechanism being normally closed by the water pressure of 115 the service pipe, connections between the steam generator and nebulizer including a restricted delivery orifice for the steam. 120

7. The combination with a nebulizer, an oil supply tank, connections between said supply tank and nebulizer, a steam generator, a water supply pipe, connections between the generator and supply pipe, in- 125

cluding a restricted feed orifice, means automatically permitting a free unrestricted flow of water or steam from said generator back into the discharge end of said water supply pipe when the steam pressure in the generator exceeds the water pressure in the supply pipe, said means including a valve mechanism normally closed by said water

pressure, and connections between said generator and said nebulizer.

In testimony whereof I affix my signature in presence of two witnesses.
